(57) **CLAIM**

I claim the ornamental design for a light emitting diode fascia, gimbal and lens, as shown and described.

DESCRIPTION

FIG. 1 is a bottom, left perspective view of a light emitting diode fascia, gimbal and lens embodying my design;

FIG. 2 is a top, right perspective view of the light emitting diode fascia, gimbal and lens of FIG. 1;

FIG. 3 is a bottom plan view of the light emitting diode fascia, gimbal and lens of FIG. 1;

FIG. 4 is a top plan view of the light emitting diode fascia, gimbal and lens of FIG. 1;

FIG. 5 is a left side elevational view of the light emitting diode fascia, gimbal and lens of FIG. 1;

FIG. 6 is a right side elevational view of the light emitting diode fascia, gimbal and lens of FIG. 1;

FIG. 7 is a bottom, left perspective view of the light emitting diode fascia, gimbal and lens of FIG. 1, with light emitting diode components shown in phantom outline for environmental purposes and not forming any part of the claimed design; and,

FIG. 8 is a bottom, left perspective view of the light emitting diode fascia, gimbal and lens of FIG. 1 with the gimbal in a pivoted position.

Features of the drawings shown in phantom outline are shown for environmental purposes and do not form any part of the claimed design.

1 Claim, 5 Drawing Sheets
